(57) **CLAIM**

We claim the ornamental design for a dispenser for quarter-folded wipers, as shown and described.

DESCRIPTION

FIG. 1 is a perspective view of a dispenser for quarter-folded wipers;

FIG. 2 is a second perspective view thereof;

FIG. 3 is a left side view thereof;

FIG. 4 is a right side view thereof;

FIG. 5 is a front view thereof;

FIG. 6 is a rear view thereof;

FIG. 7 is a top plan view thereof;

FIG. 8 is a bottom plan view thereof.

The broken lines shown represent unclaimed subject matter and form no part of the claimed design.
